CUTLERY RECEPTACLE TRAY

Harry C. Gessler, Brooklyn, N. Y., assignor to
Medco Silver Co. Inc., a corporation of New
York

Application November 22, 1949, Serial No. 128,747

6 Claims. (Cl. 206—75)

This invention relates to receptacles for cutlery or tableware, and more particularly is directed to improved storage receptacle trays for knives, forks and spoons and the like utensils in a neat, attractive and compact arrangement readily accessible for selective removal as required.

Among the objects of the invention is to generally improve devices of the character described, which shall preferably be made as a one-piece molded structure, which shall be relatively inexpensive to manufacture yet form a neat and attractive appearing tray or box for displaying and storing a wide variety of table flatware, which shall be lightweight yet adapted to withstand rough usage, which shall have a capacity for readily storing different shapes and sizes of flatware in a harmonious arrangement, which shall permit quick, convenient removal of the units individually or in a selected number, and which shall be practical and efficient to a high degree in use.

The subject matter of this application is a continuation in part of my copending application Ser. No. 84,142, filed March 29, 1942, now abandoned.

Other objects of the invention will in part be obvious and in part hereinafter pointed out.

The invention accordingly consists of features of construction, combination of elements and arrangements of parts which will be exemplified in the construction hereinafter disclosed, the scope of the application of which will be indicated in the claims following.

In the accompanying drawing in which one embodiment of the invention is shown:

Figs. 1 and 2 are perspective views of a cutlery tray constructed to embody the invention showing top and bottom sides, respectively.

Figs. 3 and 4 are cross-sectional views taken on lines 3—3 and 4—4 in Fig. 1 showing in broken lines articles of flatware in nested and upstanding supported position in compartment of the tray, and

Fig. 5 is a fragmentary cross-sectional view of a fragmentary portion of the tray taken on line 5—5 in Fig. 1 showing cradle formations for space supporting the knife handles in a fan arrangement.

Referring in detail to the drawing, 10 denotes a cutlery box receptacle tray constructed to embody the invention preferably molded of colored, opaque, transparent or translucent plastic material such as polystyrene, cellulose acetate or nylon as a one-piece structure having a top

wall 11 normally lying in a horizontally disposed plane formed integrally with peripherally down turned skirting flange wall 12 vertically disposed with relation to said wall 11 and having a setback rabbet portion 12a extending adjacent the level of said top wall 11. Said wall 12 may have a free edge 12b thereof lying substantially in a plane parallel to that of top wall 11, intermediate portions thereof being recessed at 12c to form corner legs 12d to serve as a base for tray 10 when placed on a horizontal supporting surface S, such as a table top or shelf as is clear from Figs. 3 and 4.

Also integrally formed to extend down, that is, depressed from the plane of horizontal wall 11, are a plurality of spaced elongated sunken compartments, stalls, or wells, as shown in Figs. 1, 3 and 4, at 13, 14, 15 and 16.

Sunken compartment, stall or well 13 may be sized and shaped to neatly receive a stack of nested medium or soup spoons M, well 14 to receive a stack of nested teaspoons T, well 15 a stack of nested forks F, and spaced apart wells 16 may be formed to each have fitted therein a plurality of knives K standing on edge disposed in side by side fanned relation, one of each of the utensils M, T, F and K being shown in broken lines in Figs. 1, 3, 4 and 5 to represent each stack and one of the knives, respectively.

As seen in Fig. 2 each bottom side 13a, 14a and 15a of wells 13, 14 and 15, respectively, may be formed in contour to accommodate curvatures or offsets so that bottom units of each of the various stacks rest on said respective bottom sides, as is clear from Figs. 3 and 4.

As is clear from Fig. 1, the spaced compartments or stalls 13, 14, 15 and 16 may be arranged in a neat compact pattern with the handle portion receiving ends thereof terminating in a direction toward a front side 10a of the tray 10 and the instrument receiving ends of said compartments such as, bowl of the spoons M and T, tines of forks F and blades of knives K, respectively, terminating toward a rear side 10b, compartments 13, 14 and 15 for nesting units M, T and F being arranged in a central portion of the tray flanked by compartments 16.

One feature of the invention is to provide a simple yet attractive compartment tray for either storing or displaying a complete set of table flatware and is particularly constructed for accommodating knives having relatively thick handles in a neat, attractive arrangement in a predetermined minimum space.

To this end, said compartments or stalls 16

may each be at blade ends thereof constructed with a plurality of uniformly sized and shaped open ended slits 17 formed to extend down from the plane of top wall 11 and having right angular depth extensions 17a in normally vertical extending end wall 16b of said compartments 16. Said extensions 17a may project a distance below the plane of top wall 11 for supporting blades of knives K in spaced aligned upright position at a uniform level on end wall edges 17b, each slit 17 preferably being of a width slightly greater than that of said knife blades.

Likewise, the handles of knives K are supported as a group, each on a ledge 16c spaced below the level of the plane of top wall 11, said ledges having cradles 16d formed therein for the individual fanned out spacing of the handles of each group of knives K.

Bottom sides 16a of compartments 16 may reach down beyond the level of wall edge 17b and cradles 16d to provide storage space of additional flat-ware pieces, as for example, butter knives, oyster forks and the like (not shown) and not otherwise provided for.

As seen in Figs. 1 and 2, tray 10 may be formed with transverse passageway 18 interconnecting said compartments reaching down from the plane of top wall 11 to the level of compartment bottom sides 13a, 14a, 15a and 16a to facilitate selective removal of nested spoons M and T, forks F, from compartment 13, 14 and 15 and knives K from stalls 16.

By constructing tray 10 as described above and shown in the drawings, top wall 11, peripheral side wall 12 and the walls of compartments 13, 14, 15 and 16 and passageway 18 can be made of uniform minimum thickness yet exceedingly rugged to withstand rough handling and use since a reverse or channel-shaped structure formation is provided by adjoining compartment walls, and also by walls of knife stalls 16 spaced from adjacent peripheral side wall 12, all being braced by the walls of passageway 18, thereby substantially reinforcing the construction of tray 10, as is clear from Figs. 3 and 4.

The practical operation for using tray 10 will now be apparent. Assuming that the depth of said compartments 13, 14 and 15 is made such as to accommodate the height of a stack of from eight to twelve flat-ware utensils, such as spoons M or teaspoons T or forks F, in a nested position, and stalls 16 each formed to accommodate four or six knives K in said upstanding fanned relation, each of said compartments and stalls may be filled with its respective utensils, the tray 10, covered if desired with a transparent or other fitted cover (not shown) which may engage in the set back rabbet portion 12a in the well understood manner, may be placed in a drawer or other convenient storage place. Flat-ware units M, T and F can be selectively removed in any desired number by simply reaching with the thumb and index finger into passageway 18 to straddle any selected stack of part thereof. Likewise, by similar reaching with the index finger and thumb into passageway 18 and under supported knives K, the latter may also be removed.

A novel feature of the improved construction of tray 10 is the trapezium shaped mid portion thereof flanked by right trapezium shaped knife stalls 16, said midportion having compartments 13, 14 and 15 arranged in a flare, that is fan-like relation diverging at instrument receiving ends thereof while said knife stalls 16 having open-ended slits 17, extension slits 17a, ledges 16c and cradles 16d are constructed and arranged to sup-

port knives K in reverse fan-like relation diverging at the knife handle ends thereof to form an attractive, neat display and storage receptacle of relatively minimum dimensions in which the table-ware units are easily accessible yet utilizing substantially all available space, as clearly shown in Fig. 1.

It will thus be seen that there is provided an improved cutlery receptacle tray construction whereby the several objects of this invention are achieved and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A table-ware tray comprising a one-piece molded plastic structure of substantially uniform wall thickness throughout, a rectangular top wall for said structure lying wholly in one plane, a peripheral side wall extending down from said top wall terminating in a free edge forming base supporting means, said top wall having a midportion flanked by a pair of stalls each for supporting opposite ends of a plurality of knives in spaced apart edgewise upright position, elongated sunken compartments depressed down from said top wall midportion between said stalls, said compartments being shaped and sized to receive nested stacks of table-ware and disposed so that handle portion ends of the table-ware extend in a direction toward a front side of the tray and instrument portion ends in a direction toward a rear side thereof, bottom walls of said compartments being curved to conform to the contour of the table-ware, said top wall being depressed to provide a transverse passage interconnecting said compartments and said stalls, said stalls having front and rear vertical walls, said top wall adjacent the rear vertical wall of each stall being formed with open-ended slits extending down from said top wall plane, said rear vertical wall each having depth extension slits extending in angular relation to and communicating with said open-ended slits, aligned spaced apart edges terminating said extension slits, said front vertical walls of said stalls being formed with ledges spaced below said top wall plane, said ledges having cradles for positioning knife handles in a fanned out spaced relation, and said open-ended slits and depth extension slits being sized and shaped to each receive a knife blade for support on each of said aligned edges.

2. A table-ware tray comprising a one-piece molded plastic structure of substantially uniform wall thickness throughout, a rectangular top wall of said structure lying wholly in one plane, a peripheral side wall extending down from said top wall terminating in a free edge forming base supporting means, said top wall having a midportion flanked by a pair of stalls each for supporting opposite ends of a plurality of knives in spaced apart edgewise upright position, elongated sunken compartments depressed down from said top wall midportion between said stalls, said compartments being shaped and sized to receive nested stacks of table-ware and disposed so that handle portion ends of the table-ware extend in a direction toward a front side of the

tray and instrument portion ends in a direction toward a rear side thereof, bottom walls of said compartments being curved to conform to the contour of the table-ware, said top wall being depressed to provide a transverse passage interconnecting said compartments and said stalls, means formed in opposite front and rear vertical walls of each of said stalls for supporting said knives in a fanned out position with respect to said tray rear side at a substantially uniform level with respect to said top wall plane, said top wall midportion being of trapezium shape and said compartments thereof being arranged in flared fan-like relation diverging in the direction of instrument receiving ends, thereof, and said stalls being right trapezium shaped with said midportion interfitting therebetween for supporting said knives in said fanned out position in reverse with respect to the flare of said compartments.

3. The table-ware tray defined in claim 2 in which said knife supporting means at the rear walls of said stalls are formed as open-ended slits extending along said top wall and down from said top wall plane to provide depth extension slits having aligning edges in said rear vertical walls at right angles to and communicating with said open-ended slits, said open-ended slits and depth extensions being sized and shaped to each receive a knife blade end for support on said aligned 30 edges to extend beyond said plane.

4. The table-ware tray defined in claim 2 in which said knife supporting means at the front vertical walls of said stalls have ledges spaced below said top wall plane to serve as individual cradles for positioning handles of said knives in said fanned out position.

5. The table-ware tray defined in claim 2 including bottom walls for said stalls depressed below the level of said knife supporting means to form storage compartment space thereunder.

10 6. The table-ware tray defined in claim 2 in which said stalls each have a vertical side wall spaced in parallel relation adjacent said peripheral side wall to form therewith channel-shaped stiffening structures extending along opposite sides of the tray.
